WILLIAM LANING ACKLEY, OF DALLAS, TEXAS, ASSIGNOR OF FIFTY-ONE PER CENT TO
DALLAS TAILOR'S SUPPLY COMPANY INCORPORATED, OF DALLAS, TEXAS

VALVE-STEM GUIDE

Application filed June 16, 1928. Serial No. 285,926.

This invention relates to valves and especially that type of valve designed for use in connection with steam pressing machines and adapted to control the vacuum feed on such 5 machines, and the invention has for its principal object, the provision of a novel and improved stem guide for valves of this character and purpose.

A further object of the invention resides in 10 the provision of a valve body so constructed as to meet with the requirements of said valve stem guide as regards the latter's attachment thereto, to perform the necessary function of constraining the said stem to move in a posi- 15 tively vertical plane.

Still further, the invention aims among its objects to provide a valve stem guide of economical construction which will minimize leakage resulting through constant and ex- 20 cessive wear upon the valve, valve stem and seat by reason of non-uniform movements of the stem, said guide being adapted to move the valve stem uniformly without variance from the vertical plane, thus materially re- 25 ducing the lateral strain and consequent wear upon the stem and associated parts.

With the foregoing objects as paramount, the invention has particular reference to its salient features of construction and assembly 30 of parts by which these, as well as other lesser objects are obtained and which will become manifest as the description proceeds, taken in connection with the accompanying drawings, wherein;—

35 Figure 1 represents a fragmentary front elevational view of a clothes press suggesting one use of the invention.

Figure 2 is a front view of a valve and stem 40 guide constructed according to the present invention.

Figure 3 is a side elevational view in vertical cross-section showing the vertical displacement of the valve, and co-ordinative movement of the valve stem guide, and

45 Figure 4 is a detail side elevational view of the improved valve stem guide, suggesting in broken lines, its movement in operation.

In continuing now more in detail with the 50 description of the invention and its various parts as exemplified in the attached drawings,

it may be first stated that in clothes pressing machines employing the vacuum principle of drying, effectiveness of the vacuum valve is materially reduced by reason of excessive wear upon the valve stem and consequently 55 the valve and its seat. Usually, the type of valve used for this purpose is the push-rod type and without any provisions for uniformly moving the valve stem. Ordinarily, a small disc is provided which simply abuts the protruding end of the stem, and when, through 60 constant use, disalignment occurs, the valve stem is subjected to excessive strain which ultimately brings about leakage in the valve seat. By moving the valve stem always in a 65 positive vertical plane as provided for in the present invention, only normal and expected wear results, consequently prolonging the usefulness and effectiveness of the valve and its essential parts.

Accordingly, the character 1 designates the 70 pressing machine upon which the invention is especially used, shown only to illustrate the relative position of the valve and guide when operatively applied.

The valve body 2 has integral therewith a projection 3, as especially shown in Figure 3, which projection has a bearing opening 4 therein at right angles with respect to the valve body 2. The interior mechanism of the 75 valve is of conventional nature and is not herein claimed as novel but is herein illustrated to show the action imparted thereto by the guide to be hereinafter described.

The stem 5 protrudes through the packing 6, downward through the packing gland 7, and upward movement thereof displaces the valve disc 8 in the manner indicated in broken lines in Figure 3 to open the central passage 9 and upon relieving pressure against the 80 stem 5, the inner spring 10 returns the disc 8 to normal closed position.

It has been found that the greatest wear in the assembly takes place in the gland 7, causing the packing 6 to wear, thus creating a 85 leak. It is of course possible to replace the packing and the gland and provide a new stem, without the necessity of replacing the entire valve, but it has been found to be more effective and economical to provide guide 90 95 100

means to eliminate excessive wear upon the stem and associated parts.

A lever 11 straddles the projection 3 integral with the valve body 2 and a pin 12 holds the same in pivotal relationship with the body. This lever affords a hanger for the guide, which latter is in the form of a U-shaped stirrup 13 and a similarly shaped outer bracket 14 which may or may not be integral with the stirrup but preferably rigid therewith. As exemplified in Figure 3, a recess 15 is made in the horizontal portion of the stirrup for the reception of the end of the valve stem 5.

The bifurcated ends of the stirrup 13, where they join the ends of the bracket 14 are pivotally connected to the free ends of the lever 11, in the manner shown in Figures 2 and 4, by bolts 16 and the lever being pivoted by pin 12 to the projection 3 of the body, is capable of movement as the guide assembly is moved upwardly toward the body of the valve.

Usually, upward movement of the valve stem is caused by a foot pedal, not shown, but located at a point near the base of the machine accessible to the foot, and from this pedal, protrudes the push rod 17, or generally known as the vacuum valve rod when the valve is so applied. This rod 17 is secure by nuts 18 to the cross bar of the stirrup brace 14, although this manner of securing the rod may be altered if required.

It is apparent that the guide, consisting of the stirrup 13 and brace 14, upon being urged upwardly by the push rod 17 will urge the stem 5 upward against the resistance of spring 10 to open the valve, and any tendency of the elements 13 and 14 to deviate from a positive vertical plane during such movement will be prevented by the lever 11, which latter in pivoting during the upward movement of the elements 13 and 14 carries the said elements on a straight, vertical line, in alinement with the valve stem 5.

The obvious result in constraining the guide elements 13 and 14 to so move vertically is that every movement of the stem 5 in opening and closing the valve will be positively uniform and will thus prevent wear which would otherwise prematurely impair the parts.

Manifestly, the construction shown and described is capable of considerable modification, and such modification as is in keeping with the appended claims, is also considered within the spirit of the invention.

What is claimed is:—

1. A valve stem guide including a U-shaped element embracing the end of said stem and constrained to travel in a strict plane with the latter, the constraining means comprising a lever pivotally joined to said guide and fulcrumed to the body of said valve at

a point offset with respect to the line of travel of said guide.

2. A valve stem guide including in combination with the valve, a U-shaped element embracing the end of said stem, the arms of which extend well above the end of said stem and constrained to travel in positive alinement with said valve stem, the constraining means comprising a lever arranged for pivotal movement on a fulcrum slightly offset with respect to the line of travel of said guide and having its free end pivotally connected to the arms of said U-shaped element. 70 75

3. A valve stem guide including in combination with a valve, a member embracing the end of said stem and having arms extending in the direction of the body of said valve, and means pivotally connected to the valve body for constraining said guide member to move strictly in a vertical plane with said stem. 80 85

4. A valve stem guide including in combination with a valve, a member recessed for the reception of said stem and having arms extending parallel with respect to said stem, and means pivotally connected to said arms and to the body of said valve for constraining said guide member to move in a strictly vertical plane. 90 95

5. A valve stem guide including in combination with a valve, a guide member embracing the end of said stem, a brace member rigid with respect to said guide member and having means for the reception of a valve push rod; said guide and brace members adapted to be moved upward by said push rod to actuate said stem, and means connected to said body for positively holding said members against lateral displacement during said movement to guide said stem. 100 105

6. A valve stem guide including a member embracing the end of said stem and having upwardly extending arms; and means pivotally joined to the valve body and to said arms to constrain said member to move in a strictly vertical plane to so guide said stem. 110

7. A valve stem guide including an inner member recessed to receive the end of said stem and a rigid outer member for actuating said member and to which a valve push rod is connected, and means for constraining said members to move in a vertical plane when said push rod is actuated. 115

In testimony whereof I affix my signature.

WILLIAM LANING ACKLEY. 120
